METHOD AND MEANS FOR DIRECTION FINDING

August Leib, Berlin, Germany, assignor to Tele-funkens Gesellschaft für Drahtlose Telegraphie m. b. H., Berlin, Germany, a corporation of Germany

Application January 27, 1932, Serial No. 589,100
In Germany June 15, 1926

7 Claims. (Cl. 250—11)

The present invention, which is a continuation in part of United States application #198,926, filed June 15, 1927, relates to an arrangement for directional signalling and in particular for direction finding work in wireless telegraphy. This invention is universally useful, but is illustrated as being particularly for use on vessels, automobiles, ships, or aircraft.

It is well known that for direction finding work loop or coil antennae, or other antennae having directional characteristics, are employed, and that the intensity of the signal currents set up in the aerial system by absorbed signal energy vary in accordance with the particular position of such directional antenna relative to the position of the source of signals. In using such devices, it has been found that an absolute zero, that is, a complete absence of current, in the absorption circuits can not be obtained no matter how the directional antenna is positioned with respect to the distant transmitter. Such lack of sharpness of minimum response of the absorption structure to incoming current intensity may be the result of various causes. These causes may reside either in the directional absorption structures themselves or else in effects external to the latter. Particularly on ships there is one special source of disturbance, namely re-radiations from adjacent metallic structures or wires or other conducting elements or structures mounted on the ships. This re-radiation from adjacent conducting elements to the directional aerial system results in the introduction in the circuits of currents not in phase with the current therein representative of directly absorbed signal energy. These disturbing currents result in masking the null point on the energy curve representative of the absorption characteristics of the receiver and result in a reading which does not give the true direction of the source of signals. This re-radiated energy may be of any frequency, and may be of a frequency above or below the signal frequency but is in general higher than the signal frequency. This effect of re-radiation of energy from adjacent conducting elements to the directional absorption system is known as mast effect. It must be kept in mind that the result of this out-of-phase energy in the loop circuit is to dull or mask the null point of the loop's signal absorption characteristic rather than to shift it, and the object of the present invention is to provide means to clear up or make more definite the null point of the characteristic curve rather than to shift it.

Briefly and broadly the above difficulties are obviated in accordance with the present invention by introducing into the loop circuit energy to oppose and compensate the energy induced therein from the adjacent masts or other conducting elements. 5

More in detail, the null point of the characteristic curve of the absorption system is made more sharp (i. e., energy reaches zero) by the introduction into the absorption circuit or circuits 10 associated therewith of energy opposite in phase and equal in amplitude to the disturbing energy. This may be accomplished in any manner. Applicant uses a vertical aerial coupled to the loop circuit to introduce the compensating energy. 15 It will be understood however, that directional or non-directional auxiliary antennae may be used which occasion an additional action on the receiving apparatus so that the disturbing actions are compensated and the null point rendered more definite. 20

One form of the invention is shown in the accompanying drawings in which:

Figure 1 shows diagrammatically the circuit arrangement of a loop and compensating antenna 25 arrangement and their connection with a receiver;

Figures 2 and 2a show, for purposes of illustration, the direction finder of Figure 1 as installed on a ship; 30

Figure 2b shows in detail a modification of a part of the device of Figures 2 and 2a;

Figure 3 is a curve showing the relation between loop positions and absorption characteristics of the loop; 35

Figure 4 shows the relative positions between the antennae and an inductance associated therewith; while,

Figures 5 and 6 illustrate modifications of the arrangements of Figures 1 and 2. 40

Referring to the drawings, and more in particular to Figures 1, 2 and 2a thereof, the loop antenna R comprises symmetrical energy absorption portions r_1 , r_2 closed through inductances m_1 , m_2 and a coupling inductance r . For 45 reasons which will appear more in detail hereinafter, these coils may be symmetrical and equal or unsymmetrical and unequal. The loop aerial inductance may be tuned to the signal frequency by a capacity K connected across the terminals 1, 3 thereof. Compensating energy is obtained from a vertical aerial A connected through a tuning capacity TC and coupling inductance a to ground G or equivalent countercapacity. The amount of the inductance in this vertical aerial 50

55

may be regulated by moving the points 8 and 9 along the inductance a . The inductance a is coupled as shown to the inductance r . The said auxiliary antenna A serves to introduce an additional signal potential in the loop antenna circuit. The variable capacity TC and inductance a insures that said energy may be maintained in the proper phase and amplitude to suppress and compensate currents therein due to re-radiation from adjacent structures. The loop R has one terminal connected through a connector 3 to the grid of an electron tube e , the filament of which is connected by connector 7 to the midpoint of inductance r . The other terminal of loop R is connected by lead 4 through a variable capacity vc to the anode of thermionic tube e . The voltage set-up across the portion r_2 , the conductor 2, m_2 , lead 6 and half of the inductance r by the signal is impressed across the cathode control 20 electrode impedance of e . Anode grid reactance is controlled by the condenser vc connected between the anode and the inductance r_1 .

Now, the influence of re-radiation of signal energy upon the loop antenna circuit differs according to the particular position of the vessel relative to the source of signal energy so that the requisite auxiliary antenna effect required for the compensation of the disturbing action must be varied according to the position of the ship, with the result that the coupling between the auxiliary antenna A and the loop antenna or the receiving apparatus must be varied according to the position of the ship at any given time. To make such alterations is a rather complicated task under practical conditions of working, since in case of improper or unskilled operation and manipulation of the apparatus the compensating energy will be introduced in the wrong phase and amplitude. This will cause deviations from the true bearing of the signalling source. Even in case a skilled direction finder operator is in charge the changing of the coupling relations between A and R involves a by no means inconsiderable loss of time.

Now, according to the present invention, this inconvenience is obviated thus: The auxiliary antenna A is coupled to the receiving antenna R through a coupling impedance having a variable adjustment which is automatically controlled in accordance with the movement of the loop aerial.

It has been found that the disturbance due to re-radiation changes with the change of position of the vessel in accordance with a simple periodical law. The manner in which the disturbing effect varies with rotation of the loop or turning of the ship while the loop is pointed toward a source may be seen by an inspection of Figure 2a in which two positions, 1 and 2, of the ship are indicated. From these figures it will be seen that in one case the disturbance effect on the loop is of a maximum amount, while in the other case no disturbance at all is present. Suppose the transmitter is located in the direction indicated by the arrow S. Suppose r represents the position of the receiving antenna e. g. the position of R of B represents a re-radiating mast or other conductor, whose re-radiation effect, in this position, acts in the same direction as the wave coming in from the distant transmitter.

In this particular position of the receiving loop R, no additional action from the auxiliary antenna A is required because the loop R has its plane at right angles to the wave from the source and the re-radiating member B. But the situation is different when the ship is in the position

marked 2. In this case, the excitation of the loop by the waves transmitted from B will be of a maximum amount since the plane of the loop R points toward the re-radiating member B. Hence, an equally large opposite action from the auxiliary antenna A of Figures 1 and 2 will be required to introduce compensating energy into the loop circuit. Hence, it will be seen that the action from the auxiliary antenna will vary between zero, in ship position 1 relative to the signaling source, and a maximum, in ship position 2, or between the values present when just the opposite positions are dealt with. Consequently, the variation in disturbing effect from a re-radiating member on A during a total turn of the vessel about 360 degrees can be represented by a sinusoidal curve, as shown in Figure 3. In accordance with the present invention this varying effect of the re-radiation on the loop is compensated by an opposing effect which is introduced from A to the loop circuit in amounts which vary directly with the variations in re-radiation. In the embodiment shown this is accomplished by varying the coupling between the auxiliary antenna and the receiving apparatus or frame aerial in the same manner as the intensity of the re-radiation varies. This is accomplished by arranging the coupling coils so that one thereof is rotatable with the loop, while the other one is mounted stationary on the ship so that it has no movement relative to B. The position of one of the coils (that is, the one turning with the loop) remains unvaried with respect to the loop, while its disposition with reference to the re-radiating mast will be varied as the loop is rotated. The second coil, however, is so disposed that its position with reference to the re-radiating mast remains unchanged, while its position with reference to the distance transmitter is varied. In the specific embodiment shown the coil a is fixed relative to the ship while the coil r is movable with the loop R.

The manner in which the loop, the balancing coils and the coupling inductances may be mounted on the ship will be understood by referring to Figure 2 of the drawings. In Figure 2 the coil r representative of the loop position is fixed in the plane of the loop R, while the coil a representative of the vertical aerial effect coupling is fixed to the ship. The coil r is mounted on a sleeve p clamped at q to the shaft c which supports the loop R. The loop R and coil r may be rotated by means of hand wheel b fastened to shaft c . The vertical aerial coupling coil a is stationarily secured, as indicated by members g to support d which may in turn be fastened to the ship. The coil a is stationary with respect to r , c , and R . The direction finder scale f is fastened to d and cooperates with a pointer f' secured to d to indicate the pointing position of the loop R. It will be seen that as the loop is rotated the coupling between r and a will vary from minimum, as indicated, in position 1 of 2a, where no compensating energy is induced in the loop or receiver circuit, to maximum coupling at 65 which a maximum amount of energy is induced from a to the receiver circuit or the loop. The latter position is indicated in position 2 of 2a. For convenience of illustration the coils are shown in position of maximum coupling in Figure 2.

The mutual position of coils r and a , in case of turning of the ship, can be seen from Fig. 4, where four positions are indicated corresponding to the turning of the vessel, through zero, 90, 75

180, and 270 degrees. The case here cited is particularly simple because the assumption has been made that both the transmitter as well as the disturbing source and the loop antenna are located upon a straight line. Whenever this condition is not fulfilled, the zero point of the correction curve will shift, and then a coupling would have to exist also in position 1, in other words, the position of the two coupler coils with reference to each other must be turned a certain angle.

In actual practice it may be found that in addition to the re-radiating structure B considered above, compensated as indicated above, there may be other re-radiating structures which may very well cause a constant disturbance independent of the turning movements of the ship. The present invention obviates this by the use of a fixed coupling between the auxiliary antenna circuits and the receiving circuits or loop circuit in addition to the variable coupling described above. The fixed coupling compensates the constant source of disturbance. In the present invention this fixed coupling is obtained by means of coils m_1 and m_2 in series with the loop circuit, as indicated in Figures 1 and 2. m_1 is carried on a support h_1 fastened at i_1 . This coil may be adjusted to the desired position with respect to a and fixed in said position by means of said screw i_1 . m_2 which is also in series with loop R, is mounted adjacent a on a support h_2 . m_2 is movable with respect to a as indicated. The position of m_2 with respect to a is indicated by pointer i_2 cooperating with a scale i . The position of m_2 may be varied by handle i_2 .

If the disturbing actions bear a more complicated relationship to the position or turning of the vessel, compensating of the disturbing actions can be insured by altering the mutual positions of the coupling coils according to a law different than the one hereinbefore described, that is to say, in a way other than according to a sine law. This could be accomplished, for example, by the aid of a cam, as illustrated in Figure 2b.

The non-sinuous or irregular movement of the coupling coil r with respect to the coil a may be accomplished by fixing a cam 10 to the sleeve p bolted at q to the shaft e so that said cam rotates with said shaft when the loop R is rotated. The surface of the cam 10 of varying radius acts through roller 12 on a lever 13 which oscillates a rack 15 about a point 14. The rack 15 cooperates with a pinion 16 to rotate shaft 17 to which pinion 16 is fixed. The coupling coil r is fixed to shaft 17 for rotation therewith. The roller 12 is maintained in contact with the periphery of cam 10 by spring 18 fixed at 19. The center of cam 10 may be given any shape, and is given a shape such that the coupling between a and r is varied directly as the intensity of the re-radiated energy from the one or more adjacent structures varies.

In order to realize variation of the potentials induced by the auxiliary antenna in relation to the potentials of the loop circuit, another scheme would be to vary the electrical resistance of one or both antennae in dependence upon the turn of the vessel, instead of by variation of the coupling between the antennae and the receiving apparatus.

An understanding of the last mentioned modification will be had by referring to Figures 5 and 6 of the drawings. The arrangement shown in Figures 5 and 6 is quite similar to the arrangements shown in Figures 1 and 2. In Figure 5, however, the coupling inductances m_1 , m_2 are omitted and the terminals of a are connected through leads 1 and 2 to the loop R. Here the

center point of a is grounded, and the signal voltage across r_2 is impressed between the grid and cathode of tube R as in Figures 1 and 2. The potential introduced from the vertical aerial A through coupling coil a to the loop or receiver circuit may be determined by adjusting point 20 along a resistance W in series with a . The manner in which the position of 20 along W is determined by the position of the loop is illustrated in Figure 6. In Figure 5 the sleeve p carries a pinion 21 cooperating with a second pinion 22 which drives the contact member 20 connected to A and bearing on resistance W. When the shaft c is rotated to rotate the loop, the pointer 20 is rotated, thereby varying the amount of resistance in the vertical aerial circuit and consequently determining the amplitude of the vertical aerial component introduced in the loop through coupling a , r . The resistance turns of the rheostat W may be disposed on their support in non-uniform manner corresponding to the regularity or irregularity of the desired compensating action.

The potentials induced from the auxiliary antenna, as is well known, may be brought to act directly upon the loop circuit as shown, or else upon intermediate circuits or upon direct "reception indicators." These are different well-known schemes of combination of the effects of two antennae.

In all of the above arrangements the output elements of tube e may be connected with an indicating means directly, or by way of amplifiers, rectifiers, etc. The tube e may therefore be a detector or a radio frequency amplifier. In Figure 1 the anode electrodes of e are connected with an indicator T. In Figure 2 the output electrode of tube e is connected through a capacity 24 and high resistance 25 to the input electrodes of a second tube e' which may have an indicator in the output thereof as shown or be connected with further thermionic tubes. In Figure 5 the output elements of tube e are connected with an indicator while in Figure 6 they are connected with a relay 28 which in turn is connected with an indicator T.

Having described my invention, it is understood that I do not limit myself to the form shown, but what I claim is:

1. A directional receiver to be used adjacent metallic structures which tend to re-radiate signal energy comprising, a frame aerial circuit including a plurality of series inductances, the first of which inductances is rotatable and is exposed to the direct field of the signal energy, the second of said inductances being also rotatable with said first named inductance, a third one of said inductances being stationary with respect to said rotatable inductances, and a vertical aerial circuit including an inductance coupled to said second and third inductances.

2. A directional aerial system as specified in claim 1 in which cam means is provided for controlling the coupling between said inductances.

3. A receiving system for accurately determining the line of direction and sense of direction of a signaling source including, a frame aerial, said frame aerial including a pair of rotatable inductances exposed to the signaling wave, said inductances being in series with a plurality of coupling inductances, a pair of which is fixed and another of which is movable, a circuit for symmetrically grounding said loop aerial, a vertical aerial comprising a linear conductor and tuning means, a coupling inductance connecting

said vertical aerial to ground, said coupling inductance being coupled to said movable inductance in said frame aerial circuit, means for simultaneously rotating said first named pair of inductances in said frame aerial and said movable inductance, and a thermionic translating device having its control grid connected to a point on said frame aerial circuit and its cathode connected to ground.

10 4. In a radio direction finding system, a pair of rotatable absorption members each including a plurality of turns of conducting material, a plurality of inductances in series connecting said absorption members in series to form therewith a directional antenna circuit, a connection between the electrical midpoint of the said antenna circuit and ground, a vertical aerial path, an inductance in said vertical aerial path, an adjustable coupling between said last named inductance and one of said first named inductances, and a variable coupling between said inductance in said vertical aerial path and one of said first named inductances, and cam controlled means operable in accordance with the orientation of said rotatable absorption members for adjusting the last said coupling.

15 5. A directional antenna system comprising two rotatable inductive absorption members, a first inductance mounted for rotation with said two absorption members, similar series inductances connecting the opposite ends of said first inductance to adjacent ends of said absorption members, a condenser connecting the remote terminals of said absorption members together to form therewith and with said inductances connected therebetween a tuned closed circuit, and a connection between a movable point on said first inductance and ground, said connection permitting said tuned closed circuit to be balanced with respect to ground.

6. In a directional antenna system, a first pair of similar inductances adapted to be exposed to radiant energy, a second pair of similar inductances, leads connecting said second pair of similar inductances in series between terminals of said first pair of inductances, an odd inductance symmetrically disposed in circuit between the two inductances of the second pair, a tuning capacity connected in shunt with all of said inductances to form therewith a tunable circuit, and a connection between a movable point on said third inductance and ground to permit said tunable circuit to be balanced with respect to ground.

7. In a device for receiving radiant energy and for producing currents characteristic of the direction and sense of direction of the source of said energy, a loop aerial having two portions each including a plurality of turns of conductive material exposed to the radiant energy, an inductive circuit comprising a plurality of portions in series and having a series connection between the two portions of said loop aerial, a connection between a point of electrical symmetry on said inductive circuit and ground, means including a tuning capacitor interconnecting the free ends of the turns of each aerial portion for establishing a closed circuit which may be tuned to the frequency of the radiant energy to be received, a vertical antenna, an inductance connected thereto and to earth which inductance is coupled to the first said inductive circuit and an electron discharge device having an anode, a cathode and a control grid, said control grid and said anode being respectively coupled to opposite free ends of said aerial portions and said cathode being grounded, said electron discharge device having a work circuit connected thereto for indicating the effects of the received radiant energy.

AUGUST LEIB.
